ELECTRIC FUSE

Melville F. Peters, Beltsville, Md., and John J. Phillips, Irvington, N. J., assignors to Titeflex, Inc., Newark, N. J., a corporation of New Jersey

Application March 21, 1945, Serial No. 583,962

16 Claims. (Cl. 200—113)

1

This invention relates to electrical cartridge type fuses. Such fuses in their usual application are used to open a circuit when the current flowing in the circuit exceeds a normal rating for which the circuit is designed.

In the use of electrical equipment it is found that overloads occur, such as when several current consuming devices are simultaneously started, resulting in circuit current values which would be harmful if continued. Time is a factor, however, and for relatively short periods of time such overload currents do not create any undue heating in the circuit which would cause failure of or be detrimental to either the current carrying lines of the circuits or to any equipment installed in the lines.

It is an object of this invention to provide a fuse of a construction which will permit overloads for short periods of time without destroying the fusing element but which will open the circuit readily upon continued overload.

It is a further object of this invention to provide a fuse of plug-type construction which will permit short duration over-loads without resorting to moving parts such as dash pots and springs.

A still further object of the invention is to provide a fuse which is certain in its capacity to function and which may be easily manufactured without any especially costly elements.

Other and ancillary objects of the invention may appear throughout the description, the detail drawing, and the appended claims.

In the drawing,

Figure 1 is a longitudinal cross section view through a fuse embodying our invention;

Figure 2 is a transverse section view taken on the lines 2—2 in Figure 1; and

Figure 3 is an elevation view partly in section, to show conditions within the fuse immediately prior to the time when the fuse blows or melts.

In Figures 1 and 3 are shown the plug-type cartridge fuse construction which comprises an insulating tubular body 18 constructed of glass, plastic, or any other suitable insulating material. It is preferable that this be transparent material to permit visual inspection of the interior parts of the fuse and that it be of water-proof construction for reasons which will be apparent in the description following.

Disposed at the top and bottom of the body portion are fuse caps 11 and 12 respectively, constructed of electrical conducting metal of relatively high melting temperature such as brass or copper, which are held in place in moisture

2

sealing relationship over the ends of the body portion 18 by the brass, copper, or other conducting metal ferrules 13 and 14 respectively. Ferrule construction of this kind is well known in the electrical industry and need not be elaborated upon here with the exception that it is necessary to include a sealing cement or other material at the juncture of the tube and the conducting elements 11 and 12 which will prevent moisture within the fuse body from leaking out. As an alternative construction the caps may be of one piece construction, not shown, wherein the items 11 and 13 or 12 and 14 are included as single elements rather than as two-piece assemblies.

The fusible element 16 is constructed of a relatively low melting point material such as lead or an alloy of lead and tin depending upon the current capacity desired. This fusible element is a small hollow capillary tube, disposed centrally within the fuse body and closed off at its upper and lower junctions with the fuse caps 11 and 12. In order to locate the fuse element with respect to the caps, punched indentations 16 and 16' are provided in the upper and lower caps providing a projection on the inner surface of the cap at which point the fuse element may be fixed in place in electrical contact with the caps 11 and 12 sealing the ends of the fuse element 16. The length of fusible element may be made slightly in excess of the distance between the inner surfaces of caps 11 and 12 when assembled so that a tight fit is produced to hold it in place. Further insurance of retention of this element in position may be had by slightly fusing the ends to the caps by the application of controlled heat at the indentations 16 and 16' after the caps 11 and 12 are positioned over the ends of the fuse body 18.

Two small holes 17 and 17' are provided in one wall of the fuse element, one of which is located in the proximity of the lower fuse cap and the other, in the proximity of the upper cap. A small quantity of water 19 is introduced within the tube body to an elevation above the lower hole 17 in the fuse element with the fuse in a vertical position as is required for operation. A suitable method of performing this operation would be to provide a small hole in the body of the fuse or in one of the metal caps as at 19 through which the water could be introduced, which may subsequently be sealed with a drop of solder having a higher melting point than any temperature which would be experienced in operation. Other liquids may be substituted for

water; however, in the description which follows, certain considerations are given which are based on the use of water.

There is a certain amount of capillary action within the bore of the fuse element 15, by the tubular construction of the element itself, which will carry water upwardly into the tube. This action may be increased and the functional effects of the fuse varied by filling the interior of this element 15 with a drying agent or such material as felt or glass wool. An excess of water over that shown in Figure 1 may be permitted in the fuse if it is desirable, or conversely, this quantity of water may be very slight by locating the elevation of the small hole 17 lower in the fuse. During periods of normal operating current with the fuse placed in the line, the element 15 will receive no abnormal heat transferred to it by I^2R losses, and it will remain relatively cool. In case of an overload or short circuit, the temperature of the fuse element 15 will rise rapidly. It will not reach melting temperature immediately since the water within the tube will change state and be driven off before its temperature will greatly exceed 212° F. As steam vapor is generated by transfer of heat from the fuse element to the water within the element, the vapors will be driven off through the upper hole 17 until the level of the water drops below the hole, and because of the lower temperature of the shell these vapors will condense and later tend to fall back into the lower portion of the fuse on the outside of the fuse element. Figure 3 shows a condition resulting when all of the liquid has been driven off from within the tube to the level just below the lower hole 17 and has collected in the form of minute droplets on the inner surface of the body 16, at which time the temperature of the fuse element may go beyond 212° F. and may then reach the melting point of the fusible material, thus interrupting the electrical circuit.

If the excess current in the line should at this time drop off and in case the fuse does not "blow," then the droplets will, with normal agitation, return to the lower portion of the body and will again serve to prevent immediate fusing on overload.

In case the overload drops to a normal operating current prior to the time when the heat of vaporization had driven off all the moisture from within the capillary tube, the moisture would then be returned to the lower portion of the fuse permitting continued service without interruption. Certain changes in relative size and in material may be made to permit operation at any given temperature.

The invention is illustrated in a practical but simple form of apparatus which, however, may be considerably modified so far as details of construction are concerned, without departure from the principles of the invention.

Having thus described our invention, what we claim as new and desire to secure by Letters Patent is:

1. In an electric fuse in combination, an insulating, tubular body portion, fuse caps secured to the ends of the body portion, and a hollow tubular fusible element in electrical association at its ends with the fuse caps, said fusible element having openings extending through its wall adjacent to its ends, and a supply of liquid partly filling said body portion to a prescribed level with respect to the location of one of said openings.

2. In an electric fuse in combination, an in-

sulating tubular body portion, fuse caps secured to the ends of the body portion, and a hollow tubular fusible element in electrical association and sealed off at its ends with the fuse caps, said fusible element having openings extending through its wall adjacent to its ends, and a supply of liquid partly filling said body portion to a prescribed level with respect to the location of one of said openings.

3. In an electric fuse in combination, an insulating tubular body portion, fuse caps secured to the ends of the body portion, and a hollow tubular fusible element centrally located with respect to the body portion and in electrical association and sealed off at its ends with the fuse caps, said fusible element having openings extending through its wall adjacent to its ends, and a supply of liquid partly filling said body portion to a prescribed level with respect to the location of one of said openings.

4. In an electric fuse in combination, an insulating, tubular body portion, fuse caps secured to and in liquid tight relationship with the ends of the body portion, and a hollow tubular fusible element in electrical association at its ends with the fuse caps, said fusible element having openings extending through its wall adjacent to its ends, and a supply of liquid partly filling said body portion to a prescribed level with respect to the location of one of said openings.

5. In an electric fuse in combination, an insulating tubular body portion, fuse caps secured to and in liquid tight relationship with the ends of the body portion, and a hollow tubular fusible element in electrical association and sealed off at its ends with the fuse caps, said fusible element having openings extending through its wall adjacent to its ends, and a supply of liquid partly filling said body portion to a prescribed level with respect to the location of one of said openings.

6. In an electric fuse in combination, an insulating tubular body portion, fuse caps in liquid tight relationship with the ends of the body portion, conducting metal ferrules securing said fuse caps to said body portion, and a hollow tubular fusible element in electrical association at its ends with the fuse caps, said fusible element having openings extending through its wall adjacent to its ends, and a supply of liquid partly filling said body portion to a prescribed level with respect to the location of one of said openings.

7. In an electric fuse in combination, an insulating tubular body portion, fuse caps secured to and in liquid tight relationship with the ends of the body portion and a hollow tubular fusible element in electrical association at its ends with the fuse caps, said tubular fusible element having openings extending through its wall adjacent its ends, and a supply of liquid partly filling said body portion and carried upwardly into said tubular fusible element by capillary attraction beyond its level within said body portion.

8. In an electric fuse in combination, an insulating tubular body portion, fuse caps secured to the ends of the body portion, and a hollow tubular fusible element in electrical association at its ends with the fuse caps, said tubular fusible element filled with glass wool and having openings extending through its wall adjacent its ends, and a supply of liquid partly filling said body portion and carried upwardly into said tubular fusible element by a combined action of the element surface and the glass wool surface above the level of the liquid within said body portion.

9. In an electric fuse in combination, an in-

5 insulating tubular body portion, fuse caps of relatively high melting temperature secured to the ends of the body portion, and a hollow tubular fusible element of relatively low melting temperature in electrical association at its ends with the fuse caps, said tubular fusible element having openings extending through its wall adjacent its ends, and a supply of liquid partly filling said body portion to a prescribed level with respect to the location of said openings.

10. In an electric fuse in combination, an insulating tubular body portion, fuse caps secured

to the ends of the body portion, and a hollow tubular fusible element in electrical association at its ends with the fuse caps, said tubular fusible element having openings extending through its wall adjacent its ends, and a supply of liquid partly filling said body portion to a prescribed level with respect to the location of said openings, said liquid having a boiling point which is below the melting temperature of the fusible element.
